UNITED STATES PATENT OFFICE.

JAMES POLLACK, OF NEW YORK, N. Y.

FURNACE FOR BURNING FINE FUEL.

Application filed July 13, 1925. Serial No. 43,183.

This invention relates to improvements in furnaces for burning fine fuel in suspension. In my Patent No. 1,530,321, dated March 17, 1925, I have shown a furnace in which the fuel is blown upwardly through a nozzle into a furnace chamber which is circular in cross section and which gradually enlarges in diameter from the bottom upwardly, and in which I have provided means for blowing air upwardly into the chamber adjacent the nozzle to maintain an upward draft in all parts of the chamber and to return particles of fuel or foreign substances which may drop to the bottom of the furnace. I have also shown means for forcing air into the furnace chamber at various points in its height, so as to supply the necessary oxygen for complete combustion of the gases evolved from the fuel. The present invention is in the nature of an improvement upon the invention described in said Letters Patent. It is found, in practice, that the coarser particles of material blown upwardly into the furnace through the central nozzle, owing to their inertia, rise higher than the finer fuel and are apt to be blown out of the chamber. To remedy this, I provide in each fuel injecting nozzle a spiral baffle which gives the fuel a swirling motion as it leaves the nozzle, and by this arrangement the heavier particles are thrown by centrifugal force toward the wall of the furnace, instead of being projected in a vertical line; while the finer fuel does not travel directly to the wall but takes initially a more central position in the furnace chamber. The coarser particles are thus prevented from being projected too high in the furnace, and all of the fuel injected is held in suspension.

In the present invention, I have shown the furnace in several connected sections, each section being provided with a fuel injecting nozzle and the spiral deflectors in the adjacent nozzles being reversely arranged, and I have also shown means for admitting air laterally into the several sections at different points in the height of the furnace, the air inlets being located and directed so as to cause a swirl of the fuel and gases in the same direction as the swirl caused by the respective spiral deflectors in the nozzles. In this way, the air, gases and fuel are intermingled without having the currents in one part of the furnace opposed by currents in an adjacent part.

In the accompanying drawing,

Fig. 1 is a horizontal section through the furnace;

Fig. 2 is a section on the line 2—2 of Fig. 1;

Fig. 3 is a section on the line 3—3 of Fig. 1; and,

Fig. 4 is an enlarged sectional view through one of the nozzles and adjacent parts of the furnace.

Referring to the drawing, *a* represents the outer wall of the furnace which, as shown, flares outwardly and upwardly from the bottom, and *b* indicates the combustion chamber enclosed by said wall. The lower part of the combustion chamber is divided into a plurality of compartments 1, 2, 3, and 4 by partitions 5, 6, and 7. Each compartment has a wall formed in cross section on arcs of circles and upwardly flaring, and the chamber wall above the partitions is fluted in continuation of the arcuate walls of the several compartments. Thus, the conical compartments merge into one another above the partitions, and the inner wall of the upper part of the furnace chamber has the arcuate surfaces 1^a, 2^a, etc., concentric with the axes of the fuel injecting nozzles *c*, *c'*, etc.

The fuel injecting nozzles are the same as in my patent referred to above, except that within the bore of the nozzle is arranged a spiral baffle 8, as shown in Fig. 4. The fine fuel is fed to the various nozzles by screw conveyers contained in pipes 9 and is blown upwardly through the nozzle by air admitted from a pipe 10, or a pipe 11. The spiral baffle causes the fuel and air to enter furnace chamber with a swirling motion and the coarser particles of fuel instead of being projected straight upwardly in the chamber, where they would pass beyond the finer fuel, are thrown outwardly toward the wall and are held in suspension by the upward draft from the nozzle and from the orifice 12, surrounding the nozzle through which air is forced from the pipe 10 or pipe 11.

The spiral baffles in the nozzles in the successive compartments are reversely inclined and the air as well as the fuel injected through the successive nozzles is given a swirling motion in opposite directions, as indicated by the small arrows in Fig. 1. As in the structure of my prior patent, I provide means for admitting air to the combustion chamber, through pipes *d*, at various points in the height of the furnace, for the purpose of supplying the necessary oxygen.

UNITED STATES PATENT OFFICE.

JOHN A. RIHL, OF PHILADELPHIA, PENNSYLVANIA.

COATING MACHINE.

Application filed March 21, 1922. Serial No. 545,556.

This invention relates to coating machines of the type employed for applying icing or similar coating material to cakes or other articles.

The principal object of the invention is to provide a novel and improved means for feeding the coating material to the articles having certain simplifying and improving features and characteristics hereinafter set forth.

Another object of the invention is to provide means for feeding the coating material to the coated article in a continuous stream or ribbon, and in such manner that the customary intermittent operation ordinarily found in machines of this class is eliminated.

A further object is to provide means for mechanically separating the individual coated articles which in receiving the coating material abut one against another.

A still further object of the invention is the provision of means for applying to the coated articles a granular coating substance such as grated cocoanut.

The invention further resides in certain advantageous structural features of the machine as hereinafter described.

In the attached drawings:

Figure 1, is a side elevation of the machine made in accordance with my invention;

Fig. 2, is a side elevation, the reverse of that of Fig. 1;

Fig. 3, is a plan view of the machine;

Fig. 4, is an end elevation;

Fig. 5, is a fragmentary vertical section of a portion of the machine including the hopper for the coating material and the means for feeding the material to the articles;

Fig. 6, is a fragmentary plan view of that portion of the machine illustrated in Fig. 5 with the hopper removed;

Fig. 7, is a transverse section on the line 7-7, Fig. 6;

Figs. 8, 9, 10 and 11, are views in perspective of details of the coating material feeding mechanism;

Fig. 12, is a fragmentary side elevation of the article-separating mechanism, and

Fig. 13, is a vertical section of the hopper and feeding elements for the granular coating material.

With reference to the drawings, the machine comprises a pair of main side frames

1, 1, connected by cross bars 2, 2, shown in Fig. 5. Extending through the cross bars 2 in vertically aligned pairs, one pair at each side of the machine and close to the side frames 1, 1, are bars 3, 3, which constitute the longitudinal bed-frame of the machine and which are supported at their outer ends by a pair of legs 4, 4, which latter are joined by a cross piece 5 of the same general form as the cross bars 2 which connect the side frames 1, 1, and through which cross piece the bars 3, 3, extend.

At the opposite ends of the longitudinal frame are mounted shafts, respectively 6 and 7, said shafts being mounted in bearings 8 secured to the ends of the respective vertically aligned pairs of the bars 3, and carried by each of these shafts is a roller, 9 and 10 respectively, which rollers cooperate with a second pair of rollers 11 and 12 mounted upon lateral shafts 13 and 14 supported in bearings 15 and 16 intermediate the ends of the longitudinal frame in supporting a pair of endless belt conveyers 17 and 18. Extending between the bearings 15 and 16, one at each side of the longitudinal frame and in alignment therewith, is a bearing plate 19, in which plates are formed a series of bearings 20, in which are mounted rollers 21, 21, the tops of which are substantially on a level with the tops of the endless belt conveyers 17 and 18.

Lateral supports 22 for the belts 17 and 18 are carried by arms 23, 23, which extend inwardly towards the center of the respective belts from the ends thereof, said arms being secured to the longitudinal frame of the machine, and there extends between the supports 22, 22, in the one instance, and between the support 22 and the lateral support 24, which latter extends between the tops of the legs 4, 4, flat bearing plates 25, 25, which underlie the belts and prevent them from sagging.

Mounted upon the tops of the side frames 1, 1, and suitably secured thereto is a base frame for a hopper 28, said base comprising vertical side pieces 26 and 27, between which passes the belt conveyer 17, said frame also constituting in the present instance a support for an electric motor 29 which constitutes the driving element of the machine.

The motor 29 is connected by means of a belt 30 to a pulley wheel 31 carried on the

2
end of a shaft 32, which latter is mounted in bearings near the bottom of the side frames 1. A clutch 33 provides means for connecting and disconnecting at will the 5 pulley wheel 31 from the shaft 32, there being provided a lever 34 by means of which the said clutch may be actuated. The shaft 32 carries a pinion 35 which meshes with a gear 36 on a shaft 37 also 10 mounted in the side frames 1, 1. The latter shaft 37 carries also a pinion 38 which meshes with a gear 39 upon a shaft 40 mounted in bearings in the side frames 1, 1, said latter shaft extending at each end be- 15 yond the said side frames and having secured to the extending ends sprockets 41 and 42. The sprocket 41 is connected by means of a chain 43 with a sprocket 44 on the end of the shaft 6 whereby the roller 9 20 is rotated to drive the belt conveyer 17, the conveyer 18 receiving its movement through a chain 45 connecting sprockets 46 and 47 respectively carried by the shafts 13 and 14. The sprocket 42 is connected by means of a 25 sprocket chain 48 to a sprocket 49 on one end of a shaft 50, which latter is mounted in bearings 51, 51, at the top of the hopper-supporting frame 26—27. The shaft 50 has attached thereto a roller or drum 52, the 30 function of which will now be described.

Extending across the top of the uprights 26 and 27, one at each side thereof, is a cross bar 53, which cross bars constitute a support for a box-shaped base 54 of the 35 hopper 28. An end view of the box 54 is shown in Fig. 7, the box being cut away at the sides for the reception of the drum 52.

Secured by screws 55, 55, to the inside of 40 the box 54 are a pair of arcuate plates 56, 56, the edges of which fit close to the periphery of the drum 52 and form therewith a substantially tight joint preventing the passage of any coating material between 45 the drum and the sides of the box 54.

As clearly shown in Figs. 5 and 6, a space is left at each side between the periphery of the drum and the inner edge of the cross bars 53, 53, the length of the space at one 50 side of the drum being controlled by adjustable stops 57, 57, which latter stops by reason of slots 58, 58, may be moved inwardly or outwardly to vary the length of this space 59 at one side of the drum.

55 As best shown in Figs. 5 and 7, the box 54 is provided at the under side with threaded studs 60, which latter are adapted to pass through apertures in the cross bars 53, 53, and wing nuts 61, 61, are provided upon 60 the studs for holding the box 54 in place. The studs 60 and wing nuts 61 also provide means for securing to the under sides of the cross bars 53 guides 62 and 63, shown respectively in Figs. 10 and 11, in which 65 guides are slidably mounted stops or valves

64 and 65 respectively, which latter are adapted to completely close the spaces between the drum and the sides of the cross pieces 53, 53. The guide 62 also has mounted therein a plate 66 adjustable toward and from the drum to restrict the width of the opening 59. This plate 66, as shown in Fig. 9, is provided with a downwardly extending stud 67, which projects through a slot 68 in the guide 62, a wing nut 69 being provided whereby this plate 66 may be secured to the guide.

As shown in Fig. 6, a bracket extension 70 is provided at the top of the upright 27, said bracket forming a support for a vertical pivot 71, for a bell crank lever 72. One end of this bell crank lever 72 has thereon a handle or grip 73, and intermediate the said handle and the pivot 71 the arm is pivotally secured to a clutch element 74 at one end of the shaft 50 whereby the sprocket 49, which is loosely mounted upon the said shaft, may be made fast to the shaft. The other arm 75 of the bell crank lever 72 is connected at 76 to the upright stem 77 of the stop 64, the arm also being connected by means of a link 78 to an arm 79 pivotally secured at 80 to the guide 63, and at 81 to the stop 65 which slides in the guide 63.

The movement of the stop 64 is normally greater than that of the stop 65, and this difference in movement between the respective slides is allowed for by a slot 82 at the end of the link 78 through which connection is established between the link and the 10 arm 79.

The shaft 7 which carries the roller 10 also carries a sprocket 83, which latter is connected by means of a chain 84 with a sprocket 85 carried on a shaft 86 which extends through the lower portion of a hopper 87. The hopper is mounted in the present instance upon suitable uprights 88, 88, which extend upwardly from the bars 3, 3, constituting the longitudinal frame of the machine. As best shown in Fig. 13, the hopper is at the bottom substantially funnel-shaped, and has established therein and mounted upon the shaft 86 a corrugated roller 89, which latter in rotating in the direction indicated by the arrow in Fig. 13, is adapted to feed from the hopper a contained granular material. As clearly illustrated, the mouth of the hopper directly overlies in the present instance the conveyer 18.

11 The operation of the machine is as follows:

The cakes or other articles to be coated are placed upon the conveyer 17 in the manner shown in Fig. 5, each article abutting the 12 article immediately ahead, a guide 90 adjustably secured to the plate 25 being provided for the operator so that the articles may be placed accurately in proper position upon the belt. When the foremost article 13

is directly underneath the hopper, the operator shifts the lever 73 inwardly, thereby throwing the clutch 74 into engagement and effecting rotation of the shaft 52, movement 5 of the lever withdrawing the stops 64 and 65 to permit the passage of the coating material contained in the hopper 28 through the space 59. Although a space is also left by withdrawal of the stop 65 at the opposite

10 side of the roll from the space 59, the coating material is of such consistency that the rotation of the drum 52 prevents the passage of the material through this latter space after the stop has been withdrawn.

15 Extending between the uprights 26-27 directly beneath the drum is a bar 91, the upper edge of which bears against the face of the drum and acts as a scraper for the coating material which adheres to the drum 20 in its rotation through the bottom of the hopper, this scraper causing the film or layer of the coating material to leave the drum and pass downwardly to the surface of the articles passing thereunder, as shown 25 in Fig. 5. The articles after receiving the coating material upon their upper surfaces pass on to the rollers 21 and are forced thereacross by reason of the continued rotation of the belt 17.

30 The sprocket 47 on the shaft 14 is slightly smaller in diameter than the sprocket 46 on the shaft 13, by reason of which difference the belt conveyer 18 is driven at a slightly faster rate of speed than the conveyer 17. Accordingly when the articles are forced from the rollers 21 onto the conveyer 18, the increased speed of this latter conveyer causes the article to move away from the one directly in its rear and thereby 35 break the film of coating material and completely separate the articles from each other. In passing under the hopper 87, the article then receives upon the top of the coating material a layer of a granulated cocoanut or 40 other desired granular substance. The articles are then removed from the conveyer 18.

45 It will be noted that the coating material in this machine is fed to the coated articles in a continuous stream or ribbon and without 50 waste, there being obviated the intermittent operation which ordinarily is found in machines of this type. It will also be noted that the depth of the coating on the articles may be regulated by the element 66 which 55 may be moved to different distances from the periphery of the drum. When it is desired to interrupt the operation of the machine, the lever 73 is pulled outwardly by the operator, thereby disconnecting the 60 clutch 74 and effecting the inward movement against the drum of the stops 64 and 65. By reason of the elements 57, 57, the length 65 of the opening 59 through which the material passes to the articles may be varied to suit articles of different widths, while

the element 66 may be moved toward or away from the drum to give varying widths to the space 59 and to thereby control the depth of the coating on the articles.

Considerable modification of the machine 70 herein described is possible with no departure from the essential features of the invention.

I claim:

1. In a coating machine, the combination 75 with a hopper having an opening in the bottom, of a drum mounted in said opening with the face spaced from the sides thereof, stops movably mounted at the base of said hopper and adapted to close the space between the sides of said opening and the drum, and common means for actuating said stops to either open or close said spaces.

2. In a coating machine, the combination 80 with a hopper having an opening in the bottom, of a drum mounted in said opening with its face spaced from the sides thereof, stops movably mounted at the base of said hopper for closing the spaces between the sides of the opening and the drum, mechanism for rotating said drum, and a clutch connecting the drum with said mechanism, said clutch and stops being operatively connected whereby opening of the former effects 85 engagement of the latter and vice versa.

3. In a coating machine, the combination 90 with a hopper having an opening in the bottom, of a drum mounted in said opening with the face thereof spaced apart from the sides of said opening, stops movably mounted at the base of the hopper for closing the spaces between the sides of the opening and the drum, mechanism for rotating said drum, an operating lever for effecting actuation of the drum rotating mechanism, and a connection 95 between said operating member and the stops whereby movement of the operating member to start the drum retracts the stops to uncover the spaces between the drum and the sides of said opening.

4. In a coating machine, the combination 100 with a pair of spaced supporting members, of an open bottom hopper mounted on said members, a drum mounted between said supporting members with its face spaced from the inner edges thereof and extending into said hopper, guides secured to the under side of said supporting members, and stops 105 slidably in said guides and adapted to close the spaces between the supporting members and the drum.

5. In a coating machine, the combination 110 with a hopper having an opening in the bottom thereof, a driven shaft, a drum mounted on said shaft and extending into said opening, the face of said drum being spaced apart from one side of said opening, a stop movably mounted at the base of said hopper and adapted to close the said space, 115 a clutch controlling the rotation of said 120 clutch.

shaft, and a connection between the clutch and the stop whereby actuation of one entails actuation of the other.

6. In a coating machine, the combination with a hopper, of means for conducting a plurality of articles under said hopper in a continuous strip with the articles abutting each other, means for depositing a material from the hopper onto the articles in a continuous unbroken stream, and mechanical means for separating said articles from each other after receiving the coating material.
7. In a coating machine, the combination

with a hopper, of means for conducting a plurality of articles under said hopper in a continuous strip with the articles abutting each other, means for depositing a material from the hopper upon the articles in a continuous unbroken stream, and a second conducting means adapted to receive the coated articles from the first and adapted to move at a higher rate of speed than said first conducting means whereby the coated articles are separated.

JOHN A. RIHL.
